IMPULSE-TRANSMITTER FOR AUTOMATIC TELEPHONE PLANTS.

1,142,228.

Specification of Letters Patent.

Patented June 8, 1915.

Application filed February 26, 1913. Serial No. 750,762.

To all whom it may concern:

Be it known that I, GOTTHILF ANSGARIUS BETULANDER, a subject of the King of Sweden, and resident of Södertörns Villastad, in the Kingdom of Sweden, have invented 5 certain new and useful Improvements in Impulse-Transmitters for Automatic Telephone Plants, of which the following is a specification, reference being had therein to the 10 accompanying drawings.

This invention relates to impulse transmitters for automatic telephone plants of that class, which consist of one or more successively operating impulse mechanisms, 15 each comprising an impulse effecting implement, which is adjusted by means of a pointer, lever arm or the like, and a return device for the said implement, which is wound up by the adjustment of the corresponding pointer, etc.

The main object of the invention is to simplify the manipulation of the said apparatus and consists in the return device being locked in each advanced position, while the 25 impulse effecting implement can be returned from one adjusted position to a preceding position independently of the return device, so that in this manner a wrong adjustment can be corrected immediately, without first 30 permitting the contact device to run down.

The accompanying drawings show several forms of the invention, adapted to apparatus for a number of subscribers up to 100,000.

Figures 1 and 2 are a front view and an 35 end view respectively of the apparatus. Fig. 3 is a front view of one form of the invention, the casing of the apparatus being removed. Fig. 4 shows the same apparatus viewed from the left hand side in Fig. 3. 40 Fig. 5 is a rear side view of the same apparatus; for the sake of clearness the impulse mechanisms are omitted. Fig. 6 shows the same parts as Fig. 5 but viewed from the left hand side. Fig. 7 is a section on the 45 line A to B of Fig. 5, viewed in the direction of the arrow. Fig. 8 is a side view of one of the impulse mechanisms of the same apparatus. Figs. 9 and 10 show some details of the said mechanism, viewed from the side 50 and in section. Figs. 11, 12, 13 and 14 show other forms of the invention.

The apparatus shown in Figs. 1 to 10 inclusive consists substantially of five impulse mechanisms I, II, III, IV, V, located side

by side on a base plate 1 and journaled in 55 supports 8. A shaft 3 extends through all the said impulse mechanisms and is journaled in two uprights 2 fixed to the said base plate. The shaft 3 carries five ratchet wheels 4, firmly fixed to the same, and at its 60 one end a toothed wheel 6, which by a gearing 7 is connected with a regulating screw 5 (Figs. 3 and 5). The arrangement of the impulse mechanism is shown most clearly in 65 Figs. 8, 9 and 10.

Each impulse mechanism chiefly comprises an impulse effecting member consisting of an impulse disk, 26, provided with teeth, 40, means for adjusting said impulse disk consisting of a lever or pointer, 16, and a return 70 device for said impulse disk consisting of a spiral spring, 14, a ratchet disk, 11, and a cam disk, 27. The return device is adapted to be wound up by the adjustment of the impulse disk and for that purpose there is 75 a coupling between the impulse disk 26 and the return device consisting of a shoulder, 28, provided on the cam disk, 27, and of a pin, 29, fixed to the impulse disk, 26. When the impulse disk is adjusted forwardly it 80 carries with it the cam disk 27, thereby winding up the spiral spring 14. The return device is locked in wound-up position by a pawl, 31, engaging the ratchet teeth, 10, of the disk, 11, and the impulse disk may, 85 consequently, be adjusted backward independently of the return device, if required for the correction of a wrong adjustment. The construction and operation of the impulse mechanism will be better understood 90 by the following detailed description.

The ratchet disk 11 is rotatably mounted on a stud, 9, provided on the support, 8. A cylindrical ring, 13, is fixed to said disk 11 by means of screws, 12. Inside the ring 13 the 95 spiral spring 14 is located, one end of which is fixed to the ring and the other end of which is fixed to the reduced part of the said stud 9. Mounted on the ring 13 is another ring, 15, which forms the bearing for an adjusting disk, 17, made integral with the pointer, 16, and provided with teeth, 18, cooperating with a yielding catching device, 19, 20, fixed to the support. The said catching device may, evidently, be made in one 100 piece, but the construction shown is used for the purpose stated in connection with the 105 description of the operation of the appara-

tus. To the upper part of the adjusting disk 17 a helical spring, 21, is fixed, the other end of which is secured at 22 to the support, 8. The said spring 21 tends to move the 5 disk backward, during which movement a hook, 24, pivoted to the disk 17 and acted upon by a spring 23, is caused to engage a shoulder, 25, provided on the impulse disk, 26. The disk 26 is rotatably mounted on the 10 ring 13, in front of the disk, 17, and is held in its position on the ring 13 by the cam disk 27, which is mounted outside the disk 26 and fixed to the ring 13 by screws. The cam disk 27 tends, by means of its cam surface 15 30, to disengage a pawl, 31, pivoted to the adjacent impulse mechanism and acted upon by a spring 32. Said pawl is adapted to engage the teeth, 10, of the disk, 11, of the adjacent impulse mechanism, and is provided with a pin, 33, which is acted upon by the cam surface, 30, at the end of the returning movement of the disk 27. Also the hook 24 of the adjusting disk 17 is provided with a pin 34, which bears against a shoulder 35 25 on the pointer 16, when the hook is in its raised position, the hook being thus prevented from being disengaged from the shoulder 25 of the disk 26. On the other hand the hook 24 can move freely over a 30 roller 36 provided on the impulse disk 26.

A one armed, semi-circular lever 37 is pivoted to the lower part of the support 8, which by a spring 38 is forced against the 35 pin 29 of the impulse disk 26. As shown in Fig. 9 the said lever is provided on its inner side with a projection or cam surface 39, which is acted upon by the pin 29, so that the lever 37, when occupying the position shown in Fig. 8, keeps the hook 24 out of 40 engagement with a recess formed in the impulse disk by the shoulder 25 and the roller 35. As on the other hand, the said disk is rotated, the pin 29 is caused to slide on the curve shaped surface provided on the lever, 45 so that the lever is swung inward by the spring 38 and consequently the hook 24 is brought into engagement with the impulse disk.

In connection with the above statement it 50 may be observed, that the lever 37, acted upon by the pin 29 and the spring 38, actuates the hook 24 of the adjacent impulse mechanism and that the lever 37 coöperating with the impulse mechanism I is pivoted to the upright 2 and is acted upon by the 55 suspension device for the receiver, in consequence whereof partly the fork 41 for the transmitter (Figs. 1 and 2) must be depressed, for permitting the adjustment to be 60 effected, and partly the adjustment of the pointers must be duly effected in order from the left hand side in Fig. 3, the desired number being thus always set by means of the proper pointers.

To the disk 11 two pawls 42, 43, are piv-

oted, which by springs 44 and 45, fixed to the said disk, are forced against the teeth of the ratchet wheel 4. One of the said pawls is longer than the other pawl by one half of the toothpitch, an exact and reliable adjustment being thereby insured. Consequently, the sole mechanical connection between all the impulse mechanisms and the shaft 3 running freely in the openings 46 provided in the same is constituted by the 75 pawls 42, 43 and ratchet wheel 4.

An abutment 47 is fixed to the support 8, with the upward extending part of which a tooth 48 on the impulse disk 26 is brought into contact, as the said disk is returned to 80 its position of rest by the spring 14 (Fig. 9). Instead of the said abutment 47 being rigid, as shown in the drawings, it may, evidently, be yielding, which is suitable, especially when a spring of great tension is 85 used.

All impulse mechanisms are identical as to their construction, except the impulse mechanism V, the impulse disk 26 of which is provided with a projecting cam 49 (Figs. 4, 90 6 and 7), the object of which is to keep the parts, acting upon the contact mechanism, out of contact with the remaining impulse disks, until also the impulse disk 26, 49 corresponding to the unit figure, has 95 been adjusted. Consequently, if the receiver is raised from the fork, before the pointer, corresponding to the unit figure, has been adjusted, it will result only in all the adjusted devices returning to their positions of 100 rest without acting upon the contact mechanism *i. e.* without any impulses of current being transmitted through the line.

In the base plate 1 two uprights 50 are fixed, to the top ends of which a plate 51, 105 extending longitudinally of the apparatus, is fixed. In the upward extending ends of the said plate a shaft 52 is journaled, on which a number of hooks 53, coöperating with the impulse disks, are mounted in an 110 adjustable manner. To one of two locking rings 54 mounted on the shaft 52 a helical spring 55 is fixed, the other end of which is fixed to the plate 51, so that through the action of the said spring the hooks 53, firmly 115 fixed to the shaft 52, are brought into contact with the impulse disks 26. To the shaft 52 a lever arm 56 is fixed, which by means of an insulating bushing 57, provided on its lower end, coöperates with a pin 59 fixed to 120 a contact spring 58. For the equalization of the oscillating movement of the shaft 52 and the parts mounted on the same, a counterweight is fixed to the said shaft in a yielding manner, the said counterweight consisting of a plate 60 extending longitudinally of the apparatus.

On the plate 51, fixed to the uprights 50, a guide is provided, in which the rod 62, carrying the fork 41 of the receiver, is jour- 125 130

naled (Figs. 1 and 2). The lower end of the said rod bears against a pin 64 provided on a lever arm 63. The said lever arm 63 is firmly connected or made integral with the lever arm 37, pivoted to the support 2 (Figs. 3 and 4), and is held, when the receiver is removed from the fork, in a raised position by a helical spring 65 fixed to the lever arm 63 and to the upward extending 10 part of the plate 51. A lever arm 67, pivoted to one of the uprights 50, bears against the upward extending part 66 of the lever arm 63 and is acted upon by a helical spring 68, the object of the said lever arm 67 being 15 partly to act upon the lower set of contacts, shown in Fig. 5, by means of a pin 69 provided on the lever arm, partly to coöperate by its free end with a pin 70 provided on the regulating screw 50, so that the starting of 20 the winding up mechanism is prevented, until the lever arm 67 is in its upper position, *i. e.* as the receiver is removed from its fork.

For the purpose last mentioned an additional device is provided, which coöperates 25 with the pawl 31 at the first impulse mechanism I and the construction of which is shown more clearly in Fig. 4.

To the base plate 1 an upright 71 is fixed, to which a two armed lever 72 is pivoted, 30 which is forced against the lever arm 63 by a spring 73, a pin 74 provided on the lever arm 72 acting upon the pawl 31 of the said impulse mechanism. Consequently, as the receiver is removed and the lever arm 35 63 is raised by the spring 65, also the two armed lever 72 is raised against the action of the spring 73, so that the pin 74 is lowered and acts upon the pawl 31, thus bringing the same out of engagement with the teeth 10 40 of the ratchet wheel 11.

To the base plate 1 (Fig. 6) a further upright 75 is fixed, to which a lever arm 77 is pivoted, which is acted upon by a spring 76 and the free end of which is forced 45 against the cam disk 27 of the impulse mechanism V through the action of the said spring 76, while the other end of the lever arm 77, which has a notch 78, coöperates with a projection 79 on the lever arm 67 in 50 such manner, that the end last mentioned, as the lever arm 77 is in its upper position shown in dotted lines, prevents the lever arm 67 from moving downward, the lever arm last mentioned being thus prevented 55 from engaging the pin 70 of the regulating screw 5 (Fig. 5) for the purpose stated below.

The contact springs 58 and 80 of the set 60 shown in Fig. 6 are connected with earth, while the contact spring 81 is connected with one of the line branches and the contact spring 82, when the apparatus is in its operating position, *i. e.* when the receiver is removed from its fork, is connected with the 65 other line branch.

The lower set of contact springs, Fig. 5, is adapted to switch on the circuit of the receiver, the signal circuit and the connection with earth. The top set of contact springs shown in the same figure forms a contact device, adapted to close for a moment one of the line circuits, as the receiver is put into its fork 41, but not to close the said circuit, as the receiver is removed.

The apparatus operates in the following 75 manner. During the setting of the desired number the receiver must be located in the fork 41. Consequently, the top part of the lever arm 37, belonging to the impulse mechanism I, is held in its lower position by 80 means of the rod 62 and the lever arm 63, so that the hook 24 is brought into engagement with the impulse disk 26 by the spring 23. As the pointer 16 of the impulse mechanism I is now set to the desired figure, it 85 brings with itself the impulse disk 26 and by means of the pin 29 the cam disk 27 as well as the ratchet wheel 11, firmly connected with the latter. The spring 14 is thus put under tension, and the disks 11 and 27 90 are held in the adjusted position by the pawl 31, which, acted upon by the spring 32, has engaged the teeth 10 of the disk 11. The adjusting disk 17 with the impulse disk 26 are held, against the action of the spring, 95 in the adjusted position by the catching device 19, 20, which has engaged the teeth 18 of the disk 17. The catching device 19, 20, shown in the drawings, sets in such manner, that, after the adjusting of the disk 17, 100 the said device tends to move the disk somewhat backward opposite to the direction of the adjusting movement, so that the hook 24 will rest freely in the notch of the impulse disk. At the same time as the impulse 105 mechanism I has been brought out of its position of rest, the lever arm 37 belonging to the impulse mechanism II is released, owing to the fact that the pin 29 of the impulse mechanism first mentioned has been brought 110 out of contact with the cam 39. The lever arm 37 is then swung inward by the spring 38 and releases the hook 24, which, consequently, by the action of the spring 23 is 115 brought into engagement with the impulse disk 26 of the impulse mechanism II. The pointer 16 of the impulse mechanism last mentioned is then adjusted and the described series of operations is repeated at all impulse mechanisms, until at the adjusting of 120 the last device (V) the hook 53 belonging to the same slides off the cam 49 of the impulse disk 26, so that all hooks 53 fixed to the shaft 52 are caused by the spring 55 to bear against the impulse disks respectively. 125 The adjustment is now completed and the receiver is removed from the fork 41 which results partly in the lever arm 63 being raised through the action of the spring 65, so that in the manner described above the 130

pawl 31 of the impulse mechanism I is brought out of engagement with the teeth 10 of the ratchet wheel 11 through the action of the double lever arm 72, partly in the lever arm 67 being swung upward simultaneously with the lever arm 63 and out of contact with the pin 70 of the regulating screw 5. Consequently, the impulse mechanism I is released and, acted upon by the spring 14, the ratchet wheel 11 of the said device, the cam disk 27 and, through the action of the pin 29 and the shoulder 28, also the impulse disk 26 of the same device begin to rotate, the shaft 3 and the governor 15 coöoperating with the same being at the same time rotated through the action of the pawls 42, 43 and the ratchet wheel 4. The adjusting disk 17 with the pointer 16 is, however, still retained in the adjusted position by the 20 catching device 19, 20, owing to the fact that the hook 24, as the receiver was removed and consequently the lever arm 37 was swung upward by the spring 65, has been moved out of contact with the impulse disk 26. At the same time as the impulse disk has reached its position of rest and the tooth 48 has been brought into contact with the abutment 47, the catching device 19, 20 has been moved out of engagement 25 with the teeth 18 of the adjusting disk 17 by a curve shaped part of the impulse disk, the said adjusting disk 17 being then returned rapidly to its position of rest by the spring 21, *i. e.* the hook 24 brought into 30 engagement with the shoulder 25 of the impulse disk 26. During the rotary motion of the impulse disk its teeth act upon the hook 53 on the shaft 52 and the movements of the said hook are transmitted to the contact devices 58, 80, 81, 82, 83 by means of the lever arm 56 and the pin 59, so that a number of impulses, corresponding to the effected adjustment is emitted to the line. At the same time as the impulse mechanism 40 I reaches its position of rest, the disk 27 belonging to the same acts upon the pawl 31 of the impulse mechanism II by means of the cam 30, so that the impulse mechanism last mentioned is released and starts to operate in the same manner as stated above 45 with relation to the mechanism I.

The succeeding mechanisms III, IV and V are released and operate in the same manner, the desired connection being effected 50 by the current impulses corresponding to the periods of connection respectively.

The object of rendering the adjusting disks 17 and the pointers 16 independent of the rotary motion of the remaining disks 55 11, 27, 26 during the periods of connection is to permit the connecting operation to continue without impediment, even if for any reason the pointers 16 are prevented 60 from returning to their positions of rest for

instance by holding the hand on the casing 65 of the apparatus or the like.

A further advantage, gained by the present arrangement, consists in the possibility of returning all the pointers to their positions of rest, if, after the adjustment has 70 been effected, one for some reason does not desire to call the subscriber in question or if the number has been wrongly set. As the pointers are returned, only the impulse disks are returned with the same, so that at the 75 removing of the receiver the winding up mechanisms are put in motion but no emission of impulses is effected. The apparatus operates also in the same manner, if in a similar case only the pointer of the impulse 80 mechanism V is returned, owing to the fact that all the hooks 53 are brought out of contact with the impulse disks respectively by the cam 49, as described above.

If, after the connecting operation has 85 been started, one desires for some reason not to complete the same, this is effected by putting back the receiver, such a changed connection of the conductors being thereby effected, that the remaining connecting impulses cause the restoring of the connecting apparatuses of the automatic switch, already shifted. In order to prevent the lever arm 67 from being swung downward during the said operation and stopping the 95 return movement of the remaining impulse mechanisms by bearing against the pins 70 of the regulating screw 5, the lever arm 77 is provided, which, as the mechanism V is being adjusted, occupies the position 100 shown in dotted lines in Fig. 6, in which position the projection 79 of the lever arm 67 is brought into contact with the same. Consequently, the lever arm 67 can not be returned to its position of rest through the 105 action of the spring 68, until also the impulse mechanism V has been returned *i. e.* the cam 36 of the disk 27 belonging to the same has moved the lever arm 77 downward against the action of the spring 76.

The switch apparatus described above may, evidently, be provided with any number of impulse mechanisms without the construction or the mode of action of the same being altered.

The described apparatus may be considerably simplified, if the condition is given up, that the pointers should be held in their adjusted positions, until the corresponding impulse disks have reached their positions 115 of rest. In such cases no special impulse disk 26 is necessary but the teeth 40 may be provided directly on the adjusting disk 17, as shown in Fig. 11. Owing to this arrangement the hooks 24, the levers 37 and the 120 abutments 47 are dispensed with. Instead of the pin 29, Fig. 8, a pawl 85 pivoted to the disk 17 is preferably used, the free end

of which is provided with a roller 86, which by a spring 87 is forced into the space between the teeth 88 of the cam disk 27. As the pointer 16 is adjusted the cam disk 27 and thus the ratchet disk 11 are carried with it by the pawl 85 bearing against a projection 89 on the cam disk. If during the adjustment the pointer is advanced for a too long distance, it may be returned independently of the ratchet disk 11 and the cam disk 27, during which movement the yielding coupling consisting of the pawl 85, the spring 87 and the teeth 88 facilitate the proper adjustment of the pointer and keep the same in its adjusted position and in connection with the cam disk 27, so that the disk 17 partakes in the return movement of the cam disk to the position of rest, as the pawl 31 is disengaged from the ratchet disk.

Through the provision of the catching device 85, 88 the catching devices 18, 19 mentioned above and also the springs 21 acting upon the disks 17 may be dispensed with. The adjustment of the pointers 16 in wrong order is prevented by the same being not stopped in an adjusted position, if the pawl 31 has not been released through the adjustment of the next preceding pointer. Consequently, if a pointer is adjusted in wrong order, the said pointer returns immediately to its position of rest, carrying with itself the ratchet wheel 4 and the shaft 3 without however effecting any emission of impulses.

If finger disks are used instead of the pointers 16, returning of the disks 17 can no longer be questioned and for that reason also the cam disk 27 is superfluous, owing to the fact that the disk 17 may be connected with the ratchet disk 11 and a projection on the disk 17 may be substituted for the cam 30. In such case the teeth 10 may be provided, if wanted, on the disk 17, so that also the ratchet disk 11 is dispensed with. When the apparatus is constructed in the said simplified manner, ordinary pointers may be used, provided that provisions are made, making possible corrections or wrong adjustments.

Figs. 12, 13 and 14 show another form of the regulating device combined with the simplified impulse mechanism shown in Fig. 11. Fig. 12 illustrates only the parts necessary for the explanation of the new arrangement, some parts being shown in section. Fig. 13 shows an impulse mechanism, viewed from the left hand side in Fig. 12, and Fig. 14 shows the regulating device, viewed from the right hand side in Fig. 12.

The ratchet disk 11 and the cam disk 27 are firmly connected by the ring 13, as shown in Fig. 11, and are retained in their bearing by a nut 90. The ratchet disk 11

carries a pinion 91, which is journaled at its one side in the ratchet disk and at its other side in a yoke 92, fixed to the ratchet disk. The said pinion meshes with teeth 93 provided on the support 8 and concentric with the bearing provided in said support. To the shaft 94 of the pinion a ratchet wheel 95 is firmly fixed, which co-operates with two pawls 96, 97, pivoted to a toothed wheel 98, loosely mounted on the shaft 94. The said wheel 98 meshes with teeth cut in the shaft 3 and extending along its whole length. The shaft 3 is journaled at its one end in an arm 99 fixed to one of the outer supports 8 and at its other end in a nut 106 fixed to the opposite support 8. A disk 100 is firmly connected with the end of the shaft 3 last mentioned, which disk carries two brake blocks 101, 102, which by means of plate springs 103, 104 are fixed to the periphery of the disk. The said blocks are brought by the centrifugal force into contact with the inner side of a brake drum 105, firmly connected with the nut 90.

During the adjustment of the pointer 16 the pinion 91 rolls on the teeth 93, and the toothed wheel 98 on the teeth of the shaft 3, while the pawls 96, 97 slide on the teeth of the ratchet wheel 95 without engaging the same, so that the regulator 101, 102, 105 remains inoperative. As the impulse mechanism returns to its position of rest, on the other hand, the said pawls engage the ratchet wheel 95, so that the shaft 3 is rotated and causes the brake mechanism to operate.

The object of the described gearing between the ratchet disk 11 and the shaft 3 is to facilitate the taking apart and putting together of the apparatus. After the shaft 105 has been loosened from its bearings, it can be withdrawn immediately through the openings of the supports and the latter can then be loosened independently one of the other. The same object is gained also by locating the shaft outside the periphery of the impulse disks, in which case, however, the gearing between the ratchet disk and the shaft must be arranged in different manner.

Having now described my invention, what I claim as new and desire to secure by Letters Patent is:

1. An impulse transmitter for automatic telephone systems, consisting of a plurality of impulse mechanisms each including an impulse disk, means for adjusting said disk, a return device for said impulse disk adapted to be wound up by the adjustment of the disk, means for locking the return device in wound up position, and a coupling between the adjusting means and the return device operative in a forward adjustment but permitting a backward adjustment independently of the return device.
2. An impulse transmitter for automatic

- telephone systems, consisting of a plurality of impulse mechanisms each including an impulse disk, means for adjusting said disk, a return device for said impulse disk adapted to be wound up by the adjustment of the disk, means for locking the return device in wound up position, a coupling between the adjusting means and the return device operative in a forward adjustment but permitting a backward adjustment independently of the return device, and a yielding coupling between the adjusting means and the return device.
3. An impulse transmitter for automatic telephone systems consisting of a plurality of impulse mechanisms each including an adjustable impulse effecting member, a return device for said member, a common shaft connected to all return devices, a common speed regulator actuated by the said shaft, a spur gearing forming the connection between the shaft and each of the return devices and a ratchet wheel and pawl mechanism interposed between the shaft and each of the return devices.
4. An impulse transmitter for automatic telephone systems consisting of one or more impulse mechanisms each including an adjustable impulse effecting member, a return device for said member, a pinion carried by the return device and rolling on stationary teeth during the movement of the return device and a ratchet wheel firmly connected with the said pinion and transmitting the movement by means of pawls to a toothed wheel, a common shaft rotated by the said toothed wheel and a common speed regulator actuated by the shaft.
5. An impulse transmitter for automatic telephone systems consisting of a plurality of impulse mechanisms each including an impulse effecting member, means for adjusting said member, a return device for said member, a clutch adapted to connect the adjusting means with the impulse effecting member, means operated from the return device of the next preceding impulse mechanism and adapted to disengage the said clutch and means operated from the

next preceding impulse mechanism and adapted to effect the connection between the adjusting means and the impulse effecting member by the adjustment of said mechanism.

6. An impulse transmitter for automatic telephone systems consisting of a plurality of impulse mechanisms each including an impulse effecting member, means for adjusting said member, a return device for said member, a disengageable clutch adapted to connect the adjusting means with the impulse effecting member, means for disengaging said clutch and a lever mechanism acted upon by the receiver and operating to disengage the clutch of the first impulse mechanism by taking off the receiver.

7. An impulse transmitter for automatic telephone systems consisting of a plurality of impulse mechanisms each including an impulse effecting member, means for adjusting said member, a return device for said member, a disengageable clutch adapted to connect the adjusting means with the impulse effecting member, means for disengaging said clutch, a catching device adapted to hold the adjusting means in adjusted position and means actuated by the said return device and adapted to release the adjusting means by operating said catching device.

8. An impulse transmitter for automatic telephone systems consisting of a plurality of impulse mechanisms each including an impulse effecting member, means for adjusting said member and a return device for said member, a common contact device, a motion transmitting device arranged between the several impulse effecting members and the said contact device and a retaining device at the last impulse mechanism arranged to normally hold the motion transmitting device in an inactive position.

In witness whereof, I have hereunto signed my name in the presence of two subscribing witnesses.

GOTTHILF ANSGARIUS BETULANDER.

Witnesses:

ROBERT APELGREN,
GRETA PRIEU.
